UNITED STATES PATENT OFFICE.

JOHN W. FORD, OF PHILADELPHIA, PENNSYLVANIA.

DESIGN FOR A GAGE FOR FINGER-RINGS.

SPECIFICATION forming part of Design No. 22,531, dated June 13, 1893.

Application filed February 13, 1893. Serial No. 462,206. Term of patent 14 years.

To all whom it may concern:

Be it known that I, JOHN W. FORD, a citizen of the United States, residing in the city and county of Philadelphia, State of Pennsylvania, have invented and produced a new and original Design for Gages for Finger-Rings, &c., of which the following is a specification, reference being had to the accompanying drawing, showing a part thereof.

10 The leading feature of my design for a gage for finger rings, &c., is a plate having zig-zag and corrugated edges opposite to each other.

The figure represents a plan view of a gage embodying my design.

15 In the drawing:—A designates a gage con-

sisting of a plate B, having on its side edges the graded rectangular recesses C, and the graded circular recesses D. The recesses C form a zig-zag edge, and the recesses D form a corrugated edge. On the edge of one end 20 is a rectangular recess E, and on the opposite end, a circular recess F.

What I claim is—

A design for a gage for finger rings, substantially as shown and described.

JOHN W. FORD.
